UNITED STATES PATENT OFFICE.

WILLIAM L. WALL, OF PHILADELPHIA, PENNSYLVANIA.

DISPLAY-CABINET FOR EYE-TESTING CARDS.

1,072,799.

Specification of Letters Patent.

Patented Sept. 9, 1913.

Application filed December 17, 1907. Serial No. 406,949.

To all whom it may concern:

Be it known that I, WILLIAM L. WALL, citizen of the United States, residing at Philadelphia, in the county of Philadelphia and State of Pennsylvania, have invented certain new and useful Improvements in Display-Cabinets for Eye-Testing Cards; and I do hereby declare the following to be a full, clear, and exact description of the invention, such as will enable others skilled in the art to which it appertains to make and use the same.

This invention relates to improvements in display cabinets for eye testing cards. Cabinets for displaying cards by oculists and opticians, when examining for defects in vision, have been in use. In the main, however, these cabinets are cumbersome, difficult to operate, and easily impaired; consequently, while employed to some extent, these display cabinets fail to give that degree of satisfaction desired, and in many instances oculists and opticians refuse to use these cabinets by reason of their many objectionable features.

The present invention, therefore, has for its object the provision of a display cabinet which is exceedingly simple in construction, easy of operation, and one in which liability of impairment is reduced to a minimum, the invention affording a display cabinet that can be readily positioned for use, one wherein access can be easily had to the various cards to be exhibited thereby, and one in which all of the cards are concealed from view excepting the one employed for the immediate test being made.

The invention also aims to provide in a display cabinet of the character mentioned simple and efficient means for counterbalancing the respective cards, thus enabling the same to be withdrawn from the cabinet with ease and facility, and permitting their replacing in the cabinet without interference with the other cards or disturbing the nested relation thereof.

Furthermore, the invention also has in view the production of a display cabinet wherein the testing cards are at such point within the cabinet as to increase as far as possible their distance from the observer, thus rendering the cabinet especially applicable for use by oculists whose offices are limited in size, and also wherein the interior mechanism of the cabinet may be quickly

exposed to permit convenient access to such mechanism for purposes of repairs or adjustment.

With these general objects in view, and others that will appear as the nature of the improvements is better understood, the invention consists substantially in the novel construction, combination and arrangement of parts hereinafter fully described, illustrated in the accompanying drawings, and pointed out in the appended claims.

In the drawings, Figure 1 is a perspective view of a display cabinet constructed in accordance with the present invention, the cabinet being in open position. Fig. 2 is a front elevation thereof, one of the cards being partially withdrawn therefrom. Fig. 3 is a sectional plan view on the line 3—3, Fig. 2. Fig. 4 is an inverted sectional plan view on the line 4—4, Fig. 2.

Referring in detail to the drawings, the numeral 1 designates the casing of the herein-described cabinet. The front 2, sides 3, and top 4 of this casing are entirely closed, whereby said front and sides present an unbroken surface, and thus serve to effectually conceal the cards within the casing, but it will be observed that the rear of the casing is open to permit ready access to the interior thereof for a purpose to be presently stated. One of the sides 3, however, is hingedly connected, as at 5, to one edge of a back 6, said back being in the form of a rectangular frame to the upper edge of which is connected a forwardly projecting cap piece 7. This cap piece overhangs the top 4 of the casing, and presents a finished and ornamental effect to said top when the cabinet is in closed position. In order that the casing may be held in closed relation to the back 6 an eye 8 is fixed to the back to be engaged by a latch 9 carried by the side 3 opposite to that to which the hinges 5 are connected. The rear edge of this side is notched, as at 10, to receive the eye 8, and thus permit only a sufficient portion of the eye to project at the exterior of the casing for engagement by the latch 9.

In order to support the weight of the side of the casing opposite to that to which the hinges 5 are applied, when the cabinet is in closed position, the back 6 is provided with forwardly projecting dowels 11 that enter sockets 12 formed in the rear edge of the side 3 to which the latch 9 is applied, and

thus it will be seen that the hinges 5 are assisted in sustaining the weight of the casing.

Within the casing 1, and spaced from the sides 3 thereof, are arranged a pair of guides 14. Each of these guides is provided at its inner face with a longitudinally-extending groove 15, which grooves are closed at their upper ends, and thereby provide limiting stops 15' to check the upward movement of the test cards hereinafter referred to, said guides 14 being connected to the front 2 of the casing in any suitable manner in order to be sustained therein. By spacing the guides 14 from the sides 3, as described, vertically-extending channels or passageways 16 are provided at the edge portions of the casing 1. The purpose of these channels or passageways will presently appear. Also positioned within the casing 1, and arranged in nested relation in the grooves 15 of the guides 14, is a plurality of test cards 17. These cards bear upon their faces the usual symbols arranged in different sizes for purposes of testing defects in vision, and by reason of their nested relation, and the fact that they are arranged in the guides 14, the cards 17 are movable independently of each other into and out of the casing without interference with each other. Thus, when it is desired to display any of the cards 17, the particular one by which the immediate test is to be made is drawn downwardly through the open lower end of the casing 1, a finger tab 18, or its equivalent, being applied to each of the cards 17 to enable the latter being readily grasped, and thus by exposing the respective cards the symbols or characters borne thereby may be readily viewed from the front of the casing, the exposure of the particular symbols and characters being regulated by the extent to which the card is drawn from the cabinet. The finger tabs 18 may be suitably numbered in order to facilitate the exposure of the respective cards.

It is obviously necessary that some means must be provided for holding the cards 17 within the casing 1, and by which they may be readily moved therein, and to this end each of the cards 17 has connected to its upper portion one end of a cord 19, or other flexible connection, the other ends of the cords having connected thereto counterbalances 20. These counterbalances 20 are in the form of weights, but it is manifest that any construction of counterbalance may be substituted for the weights 20. It will thus be seen that through the medium of the counterbalances 20 the cards 17 are held suspended within the casing 1, and movement of the cards may be effected with a minimum expenditure of force by reason of the fact that they are counterbalanced as indicated. It is to be observed, however, that the counterbalances are pointed at both ends to allow

them readily passing each other in their movements up and down the channels or passages 16, and to further facilitate such movement of the counterbalances 20 the front, sides and back of the cabinet are grooved, as at 21, each of said grooves receiving one of the counterbalances. At the interior of the top 4 of the casing 1 is arranged a series of guides 22. These guides are in the form of eyes, and the same are arranged in parallel rows spaced from each other, the guides of one row being opposite the spaces between the guides of the opposing row, and through these guides 22 the flexible connections 19 are passed.

By arranging the guides 22 in the manner indicated, or in a staggered relation, it will be seen that each of the guides will be substantially in vertical alinement with the particular card 17 to which the flexible connection 19 that passes through that guide is connected. Thus the flexible connections 19 are connected to the respective cards in a manner to prevent entanglement of the connections with each other, or interference thereby during the movement of the respective cards. A series of similar guides 23 is also arranged at the under side of the top 4, but said guides are located immediately above the upper ends of the channels or passages 16, said guides 23 being spaced from each other, and one of the same is arranged opposite to each of the guides 22, thus distributing the cords 19 so that the latter lie in parallel relation along the top 4, such arrangement of the cords 19 and the guides 23 in relation to the guides 22 effecting proper separation of the counterbalances 20. The counterbalances, therefore, have each a separate path of movement in relation to the others, and are perfectly free from interference in the movement of the respective cards.

In order to suspend the cabinet from a wall or other support, the back 6 is provided with suitable openings 24 for receiving screws, or their equivalent, but it is apparent that the cabinet may be suspended or held in position by any other suitable fastening means.

In the use of the herein-described cabinet the same is suspended at a suitable point, and when it is desired to test the vision of a patient the cards 17 are drawn downwardly from the casing 1, thereby exposing to view, at the front of the casing, the particular characters borne by the respective cards. It is clear that as each card is lowered the force incident thereto will cause the counterbalance 20 connected to that particular card to move in a vertical direction in the channel or passage 16 wherein that counterbalance is located, and when it is desired to replace the particular card it is but necessary to apply sufficient pressure thereto to move the same upwardly into the casing. The counterbal-

ance 20, manifestly, assists this operation, and thus it is possible to move the several cards with but a minimum expenditure of energy.

5 By arranging the cards in the nested relation described all of the same are concealed from view, and it will also be evident that the movement of the card that is being exposed may be regulated in order to dis-
 10 close at the front of the casing only particu-
 lar portions thereof, thus enabling the oculist or optician to bring to view any par-
 ticular line or lines of characters that it is
 15 desired to employ as the standard of test
 during the examination that is being made.
 It is apparent that the upward movement of
 the cards into the casing will be limited by
 20 the closed upper ends of the grooves 15, but
 such limitation of movement is not effected
 until the cards are wholly concealed within
 the cabinet. It is to be noted also that the
 25 cards are in close proximity to the back of
 the cabinet when the latter is closed, thus in-
 creasing their distance from the observer,
 which is a very desirable advantage by rea-
 son of the limited size of the offices of most
 30 oculists. The cards being confined in the
 grooves 15, instead of separate grooves, are
 concentrated in small space, and the fact
 that the casing 1 is hingedly connected to
 the back 6 affords convenient access to the
 35 interior mechanism, allowing the interior
 to be quickly exposed for purposes of re-
 pairs or adjustment. Furthermore, the des-
 ignating characters carried by the tabs 18
 allow any desired card to be withdrawn by
 40 the operator without disturbing the other
 cards. There is no limitation concerning
 the number of cards that may be employed
 in connection with the cabinet, and such may
 be increased or decreased in accordance with
 45 the needs of the oculist.

Having thus described the invention, what
 is claimed as new, and desired to be secured
 45 by Letters Patent, is:

1. A display cabinet of the character de-
 scribed, comprising a casing, a series of
 cards arranged therein and movable inde-
 pently of each other, a series of counter-
 50 balances for said cards, flexible connections
 between said cards and said counterbalances,
 a set of guides located in said casing inter-
 mediate the sides of the latter to direct the
 flexible connections to the respective cards,
 55 said guides being arranged in parallel rows,
 the guides of one row being opposite the

spaces between the guides of the opposing
 row, whereby each of said guides is sub-
 stantially in vertical alinement with one of
 the cards to enable free movement of the
 60 flexible connections, and a set of guides also
 arranged adjacent each side of the casing
 for distributing the counterbalances in re-
 lation to each other, the guides of the last
 65 mentioned sets being disposed in different
 vertical planes.

2. A display cabinet of the character de-
 scribed, comprising a casing having its
 lower end open, a pair of vertically-extend-
 ing guides arranged within said casing, one
 70 of said guides being located adjacent to each
 side edge of the casing but spaced there-
 from to provide a channel, the upper ends of
 said guides terminating at points removed
 from the top of the casing, whereby to pro-
 75 vide a space between the upper ends of said
 guides and the top of the casing, limiting
 stops arranged in the upper ends of said
 guides and closing the latter, a series of
 80 cards located in grouped relation in said
 guides and vertically movable therein and
 through the open end of the casing for indi-
 vidual display at the exterior of the casing,
 the inward movement of said cards being
 85 limited by said stops, counterbalances ar-
 ranged in the channels between said guides
 and the sides of the casing to be separated
 from said cards, flexible connections between
 said cards and said counterbalances, guide
 90 eyes arranged in the space between the up-
 per ends of said guides and the top of the
 casing and providing guiding means for
 said flexible connections in said space, and
 a back to which said casing is hingedly con-
 95 nected and providing a support for the
 latter.

3. A display cabinet of the character de-
 scribed, comprising a casing, a back for said
 casing to which the latter is hingedly con-
 nected, a series of guides arranged in said
 100 casing, a series of cards slidably mounted
 within said guides, counterbalances ar-
 ranged at the sides of said guides whereby
 to be separated from said cards, and con-
 nections between said counterbalances and
 105 said cards.

In testimony whereof I affix my signature,
 in the presence of two witnesses.
